NASAL FILTER

Hubert E. Clarke, Pittsburgh, Pa.

Application June 7, 1939, Serial No. 277,924

3 Claims. (Cl. 128—148)

This invention relates to nasal filters and has for an object to provide a filter of this type which is lighter in weight than conventional filters, easier to clean and be kept in a sanitary condition, which will more effectively filter dust, pollen and other impurities from the air breathed through the nose, and which is easy to fit and adjust.

A further object is to provide a filter of this type which will not cause irritation to the tender tissues of the nose, which will fit noses of various sizes, which will be practically invisible in use, which will not adhere to the tissues of the nose, and which will have a plurality of filtering elements to eliminate toxic qualities that hitherto proposed nasal filters have for persons who are allergic.

A further object is to provide a device of this character which will be formed of a few strong, simple and durable parts which will be inexpensive to manufacture and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

30 In the accompanying drawing forming part of this specification,

Figure 1 is a top plan view of a nasal filter constructed in accordance with the invention.

Figure 2 is a cross sectional view taken on the line 2—2 of Figure 1.

Figure 3 is a plan view, drawn to enlarged scale, of the chassis or frame of the nasal filter.

Figure 4 is a plan view of one member of the chassis with the tubular support of the nasal yoke removed.

Figure 5 is a fragmentary cross sectional view taken on the line 5—5 of Figure 3 showing the tubular eye prior to being clinched to the respective side member of the chassis.

45 Referring now to the drawing in which like characters of reference designate similar parts in the various views, the chassis of the nasal filter comprises a pair of frames 10 and 11 each constructed from a single length of wire bent to provide a straight side 14, an arcuate side 15 extending for a portion of its length parallel with the straight side, the straight side terminating in a single convolution coil 12 and the arcuate side terminating in a coil 13 having a plurality of 50 convolutions through which the single convolution

5 tion 12 is hooked, to permit adjustment of the frame sides 14 and 15 laterally relatively to each other for fitting nasal passages of various sizes.

The nasal filter frames 10 and 11 are joined together through the medium of a wire yoke 16 which fits the shape of and is adapted to bridge the bottom of the nasal septum. The yoke is attached at the upper ends to the filter frames through the medium of respective eyelets 17, best shown in Figure 5, each of which is received 10 in a coil 18 formed on the straight side 14 of a respective filter frame intermediate the ends thereof, the eyelet being clinched upon the coil as shown at 19. The ends of the yoke extend through openings 20 in the bottom flange of each 15 eyelet and each end is bent around the respective eyelet in a convolution 21 to secure the yoke to the filter frames.

The filter frames are preferably treated or 20 coated with plastics that are non-toxic. Preferably the eyelets and the yoke are coated with flesh-color lacquer or flexible lacquer lending an inconspicuous characteristic to the yoke when worn. However the filter frames may be formed of pure silver, which is non-toxic, or may be 25 silver plated.

Each filter frame is surrounded with a pad or cushion 22 of lamb's wool treated to render the wool, which is toxic to some allergic people, non-toxic.

30 The pad is secured to the respective filter frame through the medium of a gauze envelope 23 which acts as an additional filter. This gauze envelope with the mat therein forms a triple 35 filter, the lower portion of the gauze forming one filter, the mat forming another, and the upper portion of the gauze forming the third filter.

The gauze envelope is treated with a commercial solution, the formula of which is unknown to me, and marketed as "Gauztex". This treatment renders the gauze non-irritating and non-adhesive to the user's skin or hair. The adhesive qualities of the gauze envelope serve to hold the mat in place and permit frequent and 45 easy changing of the mat when necessary.

In operation, the nasal filter is thrust up into the nostrils in the position shown in Figure 2, that is with the filter frames extending horizontally, and the yoke bridging the bottom of the 50 nasal septum. Air breathed through the nose must pass through the filter, and be thoroughly filtered. The resilient frame members 10 and 11 of the filter chassis hold the filter elements snugly in place without discomfort to the wearer, 55

and prevent leakage of air around the edges of the filter elements.

From the above description it is thought that the construction and operation of the invention will be fully understood without further explanation.

What is claimed is:

1. A nasal filter including frames each constructed from a single length of wire bent to form a straight side, an arcuate side having a terminal portion extending parallel with the straight side, said sides conforming to the cross sectional shape of the nasal passage, the wire having a single convolution coil at one end, the opposite end having a multiple convolution coil, the single coil being hooked through the multiple coil for connection thereto and to permit the sides of the frame to adjust laterally relatively to each other, a yoke connecting the frames together and adapted to bridge the nasal septum, and filter means carried by the frames.
2. A nasal filter including frames, each constructed from a single length of wire bent to form a straight side, an arcuate side having a terminal portion extending parallel with the straight side, said sides conforming to the cross sectional shape of the nasal passage, the wire having a single convolution coil at one end, the opposite end having a multiple convolution coil,

the single coil being hooked through the multiple coil for connection thereto and to permit the sides of the frame to adjust laterally relatively to each other, each frame having a coil formed on its straight side intermediate the ends thereof, an eyelet disposed in the last named coil, a yoke adapted to bridge the nasal septum and having a coil secured to each eyelet, and filter means carried by the frames.

3. A nasal filter including frames each constructed from a single length of wire bent to form a straight side, an arcuate side having a terminal portion extending parallel with the straight side, said sides conforming to the cross sectional shape of the nasal passage, the wire having a single convolution coil at one end, the opposite end having a multiple convolution coil, the single coil being hooked through the multiple coil for connection thereto and to permit the sides of the frame to adjust laterally relatively to each other, each frame having a coil formed intermediate the ends of its straight sides, an eyelet disposed in the coil, a yoke adapted to bridge the nasal septum and having a convolution secured to each eyelet, a filter pad surrounding the eyelet and the respective frame, and a gauze envelope enveloping the filter pad.

HUBERT E. CLARKE.
